UNITED STATES PATENT OFFICE.

CLARENCE A. MICHEL, OF CLEVELAND, OHIO, ASSIGNOR TO THE GUIDE MOTOR LAMP MANUFACTURING COMPANY, OF CLEVELAND, OHIO, A CORPORATION OF OHIO.

HEADLIGHT.

Application filed August 22, 1924. Serial No. 733,511.

This invention relates to lamps such as used on automobiles, motor busses and similar vehicles, and has particular reference to an improved manner of constructing the 5 lamp casing and also for an improved arrangement for focusing the lamp with respect to the reflector.

Heretofore it has been customary to construct the lamp casing by drawing the same 10 from a single piece of metal such as brass. However, this method of shaping the lamp casing has encountered certain difficulties which are of a serious nature when constructing a head lamp of the drum type. The 15 chief difficulty is due to what is commonly referred to as the aging of the metal which manifests itself by splits and other defects due to the drawing operation. These defects may occur at the time the lamp casing is 20 manufactured but more often occur at some later time when the lamp is in use.

It is the primary object of the present invention to overcome the aforementioned defects by constructing the lamp casing of a 25 plurality of sections which are clamped together so as to avoid the operations of soldering, brazing or similar methods of uniting the parts together.

Another object is to provide a particularly 30 simple and inexpensive method of constructing the lamp casing so that the same may be easily assembled and which shall provide a dust-proof and water-proof housing for the lamp reflector and associated parts.

Another object is to provide a novel seal 35 between the housing and door so as to exclude dust, water and other elements from the interior of the casing.

A still further object is to provide a particularly 40 simple and efficient form of focusing device whereby the operator is provided a convenient means for focusing the lamp with respect to the reflector and the desired position maintained.

With these and other objects in view, the 45 invention consists in the various novel features of construction and arrangement or combination, all of which will be fully described hereinafter and pointed out in the 50 claims appended hereto.

In the drawing accompanying and forming 55 a part of this application, Fig. 1 is a front elevation of a head lamp constructed in accordance with my invention; Fig. 2 is a vertical sectional view taken on the line

2-2 of Fig. 1; Fig. 3 is a detail in plan showing the clamping means for retaining the parts of the housing together; Fig. 4 is a fragmentary view in elevation of the central portion of the rear of the lamp casing; 60 and Fig. 5 is an end elevation of the focusing nut which is adapted to cooperate with the portion of the casing shown in Fig. 4.

In constructing a lamp casing in accordance with my invention, I provide a rear 65 section 1, a central section 2, and a front section 3. The rear section 1 is provided adjacent its peripheral edge with an inwardly turned portion 4 and a rearwardly turned portion 5. The remainder of this rear section 70 may be of any suitable shape for the purpose of ornamenting the same and is shown as being provided with a circular bead portion 6 and an outwardly flared central portion 7. The central section 2 of the 75 lamp casing is substantially cylindrical in form and each peripheral edge thereof is deflected inwardly as indicated at 8 and then outwardly to define a collar 10. The forward section 3 of the lamp casing has the 80 outer peripheral edge thereof deflected inwardly to define a flange 11 and the inner peripheral edge is turned inwardly as indicated at 12. A portion 13 intermediate the 85 inner and outer edges is embossed outwardly and provided with a plurality of apertures to receive the clamping bolts 14. In assembling the lamp casing thus far described the rear section is fitted to one end of the 90 central section so that the inturned portions 4 and 8 of these sections are in contact, and the collar 10 snugly engages the rearwardly turned portion 5. The front section is fitted to the central section in a similar manner so that flange 11 engages collar 10 on the opposite end of the central section. The bolts 14 are then inserted through the aforementioned 95 apertures in the embossed portion 13, and these bolts are threaded into suitable clamping irons 15, each of which is provided with 100 a hook portion 16 which is adapted to engage in the channel defined by the inwardly and rearwardly turned portions of the rear section. The bolts are then tightened which 105 serves to draw the sections in tight relationship, and a lock nut 17 threaded on each bolt retains the parts in adjusted position.

A reflector 20 has the edge portion thereof provided with a plurality of inwardly directed tabs 21 which are adapted to seat 110

within apertures formed in the front section 3 of the lamp casing and thereby prevent rotation and movement of the reflector with respect thereto.

5 The edge portion of the reflector is also provided with a plurality of outwardly directed tabs 22 which, together with the marginal portion 24 of the reflector, define channel segments that receive a circular cork gasket 25. The portions 26 of the reflector intermediate the tabs 21 and 22 are adapted to contact with the lamp casing and thereby provide a seat for the reflector.

15 A door 27, of any suitable construction and having a transparent pane 28, is hinged to the casing as indicated at 29 and is adapted to contact with the cork gasket to form a tight seal with the casing. A suitable latch 30 is positioned diametrically opposite the 20 hinge and serves to hold the door in closed position.

25 The central section of the casing has an inner plate 31 and an outer plate 32 fastened thereto by means of rivets 33 and these plates serve to fasten an attaching lug 34 to the lamp casing so that the same may be supported on the vehicle.

30 The focusing mechanism consists of a lamp socket sleeve 40 which is rigidly fastened to an arm 41, the rear end whereof is bent over and provided with an aperture to receive a bolt 42 which is non-rotatively mounted therein. This bolt projects through the rear of the lamp casing and is threaded into an adjusting nut 43 which is swiveled in an aperture formed in the central portion of the rear section of the casing. A coil spring 44 is interposed between the lamp casing and arm 41 and serves to place a tension on the threads of the bolt and adjusting nut. The central portion of the rear section of the lamp casing is slightly depressed as indicated at 45 and this depressed portion is provided with a plurality of embossed semi-spherical projections 46. The face of the adjusting nut which is in contact with the depressed portion 45 is provided with a plurality of semi-spherical apertures 47 which are adapted to receive the projections 46 and thereby retain the parts in the desired position.

35 In operating the focusing adjustment, it is only necessary to rotate the adjusting nut

(which is preferably knurled to afford an easy grasp for the operator) which in turn moves the bolt 42, arm 41 and socket 40 longitudinally with respect to the reflector. The projections 46 ride into and out of engagement with apertures 47 as the adjusting nut is turned, and when these projections are seated in the apertures the adjusting nut is normally held against rotation due to vibration or jolts of the machine.

40 Having thus described my invention, what I claim is:

45 1. A headlight casing of the class described comprising a central section, a forward section, and a rear section, said central section having each of its peripheral edges shaped to provide a collar at the front and rear side thereof, said front section having its peripheral edge shaped to provide a flange adapted to engage and rest on said front collar, said rear section being shaped to fit and rest on said rear collar, clamping 50 irons engaging said rear section and bolts extending through said front section and clamping irons to hold said sections together and means for retaining the parts in holding position.

55 2. A head light comprising a central section, a front section and a rear section, said central section having each of its peripheral edges deflected inwardly and then outwardly to define a collar at the front and rear side thereof, said front section having its outer peripheral edge shaped to define a flange adapted to engage and fit the front collar and having a plurality of apertures therein, said rear section being provided adjacent its peripheral edge with an inwardly turned portion and a rearwardly turned portion defining a channeled portion adapted to engage and fit the rear collar, clamping irons engaging in said channeled portion and bolts 60 extending through the apertures in said front section and through said clamping irons whereby to secure said sections in tight relationship, a lens positioned over the front of said front section and a rim holding said lens in place, a source of light and a reflector arranged within said casing, and means for adjusting the position of said source of light.

65 In testimony whereof, I hereunto affix my signature.

CLARENCE A. MICHEL.
